UNITED STATES PATENT OFFICE.

BENJAMIN WOLHAUPTER, OF NEW YORK, N. Y., ASSIGNOR TO THE RAIL JOINT COMPANY,
A CORPORATION OF NEW YORK.

INSULATING RAIL-JOINT.

No. 922,742.

Specification of Letters Patent.

Patented May 25, 1909.

Application filed September 20, 1906. Serial No. 335,521.

To all whom it may concern:

Be it known that I, BENJAMIN WOLHAUPTER, a citizen of the United States, of New York city, in the county of New York and State of New York, have invented certain new and useful Improvements in Insulating Rail-Joints; and I do hereby declare that the following is a full, clear, and exact description thereof, reference being had to the accompanying drawings, and to the letters of reference marked thereon, which form a part of this specification.

This invention relates to improvements in rail joints of that class in which the joint 15 embraces a base-plate which supports the ends of the rails, two joint bars and a longitudinal stiffening or girder-plate, and more especially to means for electrically insulating the ends of the rails from each other in a 20 joint of the kind stated.

The invention consists in the matters hereinafter described and pointed out in the appended claims.

As shown in the accompanying drawings:—Figure 1 is a plan view of the rail joint embodying my invention. Fig. 2 is a side elevation of the same with parts broken away, to show the meeting ends of the rails. Fig. 3 is a transverse section, taken upon line 3—3 of Fig. 2. Fig. 4 shows my invention as applied to a form of joint having stiffening or girder-plates at both sides of the rails. Fig. 5 shows a form of rail-joint in which provision is made for tightening the 35 rails downwardly against the insulating layer interposed between the same and the base-plate. Fig. 6 shows a modification of the construction shown in Fig. 5.

As shown in the drawings, A A indicate 40 the meeting ends of the rails, B a horizontal base-plate on which said meeting ends of the rails rest, and C C¹ two wooden joint bars which are fitted between the under faces of the rail heads and the top surfaces of the 45 base-flanges of the rails.

E indicates a longitudinal, vertically arranged, stiffening or girder-plate located in contact with the outer face of one of the joint bars and having interlocking engagement at its lower margin with the adjacent side margin of the base-plate B in such manner that it is laterally movable or adjustable 50 with respect to the base-plate but is held from vertical movement relative to the base-

plate throughout its length, so that it serves 55 as a stiffening member for the base-plate.

D D indicate track-bolts which are inserted through the rails, the joint bars and the girder-plate, for clamping said parts together.

The base-plate is provided, on its upper face at the outer side of the rail seat, with an inwardly facing, longitudinal shoulder b against which laterally bear the adjacent side margins of the base-flanges of the rails. Said shoulder b is designed to take the lateral thrust on the rails due to pressure on the inner edges of the rail-heads of the wheel flanges, and the base-plate is, therefore, arranged with the shoulder b at the outer sides 65 of the rails. The base-plate is provided near its inner margin with spike holes b¹ b¹ through which are inserted spikes, shown at F, in Figs. 2 and 3, for holding the base-plate to the ties and to prevent any outward 70 shifting or movement of the base-plate on the ties.

To provide for the interlocking connection of the outer margin of the base-plate with the girder-plate E, a construction is provided as follows: On said outer margin of the base-plate is formed a longitudinal, outwardly extending, horizontal flange B¹ located above the level of the bottom surface of the base-plate. The lower part of the girder-plate E is shaped to surround or embrace the flange B¹, and for this purpose is extended outwardly over the top of said flange and has at its lower margin an inwardly extending flange e which projects beneath the flange B¹ 80 of the base-plate; said flange e with the part of the girder-plate above it forming a groove E¹ having horizontal top and bottom surfaces and adapted to receive the said flange B¹ on the base-plate. The said girder-plate is shown as having a bottom horizontal bearing surface which is flush with the horizontal bottom surface of the plate and is thereby adapted to rest on the ties. The girder plate is shown as also provided at its lower 85 margin with an outwardly extending, horizontal flange E² which forms with the flange e a flat, horizontal bearing surface on the girder-plate, located in the same horizontal plane with the bottom surface of the base-plate 90 and adapted for contact with the ties. The outwardly extending flanges E² are preferably provided with apertures e¹ e¹ through 95 100 105

which spikes, one of which is shown at F¹ in Fig. 3, may be driven to hold the girder-plate in contact with the ties. These apertures will be transversely elongated or will have the form of open notches, as shown, in order to permit the girder-plate to be shifted toward the base-plate in tightening the joint, as hereinafter described. The inner vertical face of said girder-plate E is arranged approximately in line with the shoulder b of the base-plate, while the adjacent joint bar C¹ is made of a width equal to the distance from the web of the rail to the outer margin of the base-flange thereof, so that when the base-flange is in bearing against the shoulder b of the base-plate, the main part of the girder-plate will rest or bear against the said joint bar C¹. The groove E¹ in the girder-plate is, moreover, made of greater depth horizontally than the width of the flange B¹ of the base-plate which enters the same, so as to provide capacity for the lateral shifting of the girder-plate relatively to the base-plate, as may occur in tightening the joint, it being understood that the base-plate B is permanently secured in position upon the ties, and that any outward movement of the rails from the normal position thereof is prevented by contact of the outer margins of the base-flanges thereof with the shoulder b.

J J indicate metal washer-plates or straps, one for each rail end, which rest against the outer face of the joint bar C. Each of said straps is apertured at its ends to receive the two bolts D D which pass through one of the rails.

To provide means, in a joint made as described, for electrically insulating the ends of the rails from each other, a sheet or layer G of insulating material, such as vulcanized fiber, is placed between the base-flanges of the rails and the top surface of the base-plate. The side margin of said sheet or layer G is extended to form a part G¹ which is bent upwardly so as to extend between the shoulder b of the base-plate and the adjacent side face of the base-flange of the rail and also between the girder-plate E and the joint bar C¹ so that it will be held or clamped between said parts and the entire sheet will be thereby held in place and prevented from becoming shifted endwise from its place. Said marginal part G¹ of the insulating layer is shown as extending to the top of the girder-plate E, but this is not essential, as the insulating layer will perform its function if its upturned part is carried upwardly past the base-flange of the rail far enough to insulate the same from the shoulder b and the adjacent parts of the girder-plate above said shoulder.

Insulating thimbles H H surround the bolts D between the same and the girder-plate, the holes in which latter are made large enough to receive said thimbles, and

insulating washers I I are located between the heads of the bolts, and the outer face of the girder-plate. Between the abutting ends of the rails is located an insulating plate or layer K. The joint bars C C¹ being made of wood or of non-conducting material, the ends of the rails are, by the employment of the insulating layers between the rails, the base-plate and the girder-plate and between the girder-plate and the ends of the bolts which engage the same, electrically insulated from each other.

In the form of joint embodying my invention shown in Fig. 4 the construction is generally like that shown in the figures above described, with the exception that two girder-plates are employed instead of one. In this instance, the base-plate J has inwardly facing, longitudinal shoulders j j¹ at opposite sides of the rail-seat thereof, and is provided with outwardly extending, horizontal flanges J¹ J² at its side margins. The two girder-plates L and M are provided, near their lower margins, with horizontal grooves L¹ M¹, adapted to receive the outwardly extending flanges J¹ J² of the base-plate J. The wooden joint bars K K¹ are interposed between the webs of the rails, and the said girder-plates L and M. Track-bolts, one of which is shown at O, are inserted through both of the girder-plates, the joint bars and the rails.

A layer N of insulating material is interposed between the base-flanges of the rails and the base-plate. Said layer N is made wider than the base-flanges of the rails and its side margins are bent up between the margins of the base flanges of the rails and the shoulders j j¹, which latter are located at such distance apart as to afford room for the marginal parts of the insulating layer. At one side of the base-plate, preferably that adjacent to the girder-plate M, the margin of the insulating layer N is extended upwardly between the wooden joint bar and the girder-plate, in such manner that it will be clamped between said parts and the layer thereby held in place. The ends of the track-bolts O are insulated from the girder-plates L and M, by means of insulating thimbles or sleeves o and washers o¹ in the same manner as before described.

In Fig. 5 I have shown still another form of insulating joint embodying my invention, wherein provision is made for tightening the ends of the rails against the insulating layer beneath them, in case said insulating layer becomes to a greater or less degree compressed under the heavy loads coming thereon in the use of the joint. In this instance, the joint embraces a base-plate P like that shown in Fig. 4, wooden joint bars Q Q¹ having downwardly and outwardly inclined outer faces, and metal girder-plates R and S, which, in their general construction are like the girder-plates L and M of Fig. 4, and are

similarly interlocked with the side margins of the base-plate, but the upper parts of which have downwardly and outwardly inclined inner faces for contact with the correspondingly inclined, oblique outer faces of the joint bars Q and Q¹. In this instance, the wooden joint bars Q Q¹ are shown as having their upper surfaces below and free from contact with the under surfaces of the rail-heads. In said Fig. 5, U indicates a layer of insulating material interposed between the base-flanges of the rails and the base-plate P, and the side margins of which are extended upwardly between the side edges of the base-flanges of the rails and the inwardly facing shoulders on the base-plate. The track-bolts, one of which is indicated by T, in this instance extend through the girder-plates R and S, the joint bars Q Q¹ and the holes in the rails in the same manner as before described, the said track-bolts being insulated from the said girder-plates by insulating thimbles t t and washers t' t'. When in this form of the joint the track bolts are tightened, the girder-plates are not only drawn against the joint bars and the latter against the rails, but, by reason of the oblique contact surfaces between the girder-plates and the joint bars, the latter are forced downwardly toward the base-plate, with the effect of forcing or clamping the base-flanges of the rails rigidly in contact with the insulating layer U. Said insulating layer U is usually made of vulcanite or other material which is, to some extent, compressible, and which, under the heavy loads coming upon the ends of the rails above the joints, will, in time, become to some extent permanently compressed or reduced in thickness. Said compression of the insulating layer will necessarily result in some looseness in the joint and the purpose of the construction described is to enable the rail ends to be brought to a firm bearing against the insulating layer by the tightening of the track-bolts.

In Fig. 6 I have shown a construction somewhat different from that shown in Fig. 5, and adapted to similarly provide for taking up looseness in the joint, due to compression of the insulating layer between the ends of the rails and the base-plate. In this instance, the joint embraces a base-plate V like that shown in Figs. 4 and 5, two joint bars W W¹ which are in contact both with the base-flanges of the rails and with the heads of the same, and with two stiffening girder X and Y which are interlocked with the side margins of the base-plate V, in the same manner as hereinbefore set forth, and track-bolts inserted through the girder-plates, joint-bars and rails, one of which is shown at Z, and which are insulated from the girder-plates by insulating sleeves z z and washers z' z'. In this instance, the girder-

plates X and Y are provided at their upper margins with inwardly extending flanges x and y having oblique lower faces adapted for contact with outwardly and downwardly inclined top surfaces w w¹ formed on the joint bars W W¹, and said girder-plates also have near their lower margins, above the base-plate, inwardly extending horizontal flanges x¹ y¹ having inclined or beveled lower faces adapted for contact with downwardly and outwardly inclined faces w² w³ forming the bottom walls of two longitudinal grooves, formed in the outer faces of the joint bars W W¹ and into which said flanges project. In this construction the drawing inwardly of the two stiffening girders X and Y by the tightening of the track-bolts, has the effect of forcing the joint-bars downwardly against the base-flanges of the rails, in the same manner as before described in connection with Fig. 5, while the presence of the inwardly extending flanges x x¹ y y¹ on the girder-plates, has the effect of greatly increasing the strength or rigidity thereof.

I claim as my invention:—

1. An insulating rail joint comprising a base-plate provided with a rail-abutting shoulder, a longitudinal girder-plate having interlocking and laterally movable connection at its lower margin with the adjacent side margin of the base-plate, the contact surface of the base-plate and girder plate being horizontal and affording horizontal, lateral movement of the girder plate relatively to the base-plate, a joint bar of insulating material interposed between the rails and the said girder plate, an insulating sheet or layer interposed between the base-plate and its shoulders and the rails, and track bolts inserted through the said girder-plate, the joint bar and the rails.

2. An insulating rail joint comprising a base-plate provided with two rail-abutting shoulders, two longitudinal girder plates having interlocking connection at their lower margins with the adjacent side margins of the base-plate, the contact surfaces of the base-plate and girder plates being horizontal and affording horizontal, lateral movement of the girder plates relatively to the base-plate, joint bars of insulating material interposed between said rails and said girder plates, an insulating sheet or layer interposed between the base-plate and its shoulders and the ends of the rails, and track bolts inserted through the said girder plates, joint bars and the rails.

3. An insulating rail joint comprising a base-plate provided with two rail-abutting shoulders, two longitudinal girder plates having interlocking connection at their lower margins with the adjacent side margins of the base-plate, the contact surfaces of the base-plate and girder plates being horizontal and affording horizontal, lateral movement

of the girder plates relatively to the base-plate, joint bars of insulating material interposed between the said rails and said girder plates, an insulating sheet or layer interposed between the base-plate and its shoulders and the ends of the rails, and track-bolts inserted through said girder plates, joint bars and the rails; the contact surfaces between the said girder plates and the joint bars being downwardly and outwardly inclined.

4. An insulating rail joint comprising a base-plate, provided at its side margins with rail-abutting shoulders and with horizontal, outwardly extending flanges, located above the level of the bottom surface of said base-plate, two longitudinal girder plates provided at their lower margins with longitudinal grooves adapted to receive the said outwardly extending flanges on the base-plate,

said grooves and flanges having horizontal contact surfaces, joint bars of insulating material interposed between the said rails and the said girder plates, an insulating sheet or layer interposed between the said base-plate and its shoulders and the ends of the rails, and track bolts inserted through said girder plates, joint bars and the rails; the contact surfaces between said joint bars and girder plates being downwardly and outwardly inclined.

In testimony, that I claim the foregoing as my invention I affix my signature in the presence of two witnesses, this 14th day of September A. D. 1906.

BENJAMIN WOLHAUPTER.
